SUBSTITUTED 3,4 - DIHYDRO - 3 - PHENYL-4-HYDROXY-4-[(AMINO)ALKOXY (OR ALKYLTHIO)]PHENYL}ISOTHIOCROMAN

Ronnie R. Crenshaw, De Witt, N.Y., assignor to Bristol-Myers Company, New York, N.Y., a corporation of Delaware

No Drawing. Filed Aug. 24, 1964, Ser. No. 391,789
13 Claims. (Cl. 260—293.4)

This invention relates to novel compounds. More particularly, this invention relates to novel compounds which possess valuable utility as oral antifertility agents, and relates to intermediates useful in the preparation thereof. In another aspect, this invention relates to a novel method of inhibiting pregnancy.

It is an object of this invention to provide a new class of chemical compounds. It is another object of the present invention to provide novel compounds having antifertility activity. It is a further object of the present invention to provide a novel method of inhibiting pregnancy.

These and other objects which may appear as the specification proceeds are achieved by this invention which comprises the provision of compounds selected from the group consisting of compounds having the following formula

(I)

and the pharmaceutically acceptable nontoxic salts thereof. In Formula I,

n is a whole integer from 1 to 6 inclusive;

*R*¹, *R*², *R*³ and *R*⁴ each represent a member selected from the group consisting of hydrogen, chloro, bromo, iodo, fluoro, trifluoromethyl, (lower)alkyl, (lower)alkoxy, di(lower)alkylamino, di(lower)alkylsulfamyl, (lower)alkanoyl, phenyl, phenoxy, benzyl and cycloalkyl radicals having from 5 to 7 carbon atoms inclusive, e.g. cyclopentyl, cyclohexyl and cycloheptyl;

*R*⁵ and *R*⁶ each represent a member selected from the group consisting of (lower)alkyl, (lower)alkenyl, (lower)alkynyl, phenyl, phenyl(lower)alkyl, cycloalkyl radicals having from 3 to 7 carbon atoms inclusive, e.g. cyclopropyl, cyclobutyl, cyclopentyl, cyclohexyl and cycloheptyl, and when taken together with —N<, constitute a heterocyclic ring selected from the group consisting of pyrrolidino, (lower)alkylpyrrolidino, di(lower)alkylpyrrolidino, piperidino, (lower)alkylpiperidino, di(lower)alkylpiperidino, morpholino, (lower)alkylmorpholino, di(lower)alkylmorpholino, tetrahydropyridino, e.g. 1,2,5,6-tetrahydropyridino, (lower)alkyltetrahydropyridino, di(lower)alkyltetrahydropyridino, *N*'-(lower)alkylpiperazino, *N*'-(lower)alkyl(lower)alkylpiperazino, *N*'-(lower)alkyl - di(lower)alkylpiperazino, hexamethyleneimino, (lower)alkylhexamethyleneimino, di(lower)alkylhexamethyleneimino;

X is a member selected from the group consisting of oxygen and sulfur.

The pharmaceutically acceptable nontoxic salts include the organic and inorganic acid addition salts, e.g., those

2

prepared from acids such as hydrochloric, sulfuric, sulfamic, tartaric, fumaric, hydrobromic, hydriodic, glycolic, citric, maleic, phosphoric, succinic, acetic, nitric and the like.

5 The term "(lower)alkyl" as used herein means both straight and branched chain alkyl radicals containing from 1 to 8 carbon atoms, e.g. methyl, ethyl, propyl, isopropyl, butyl, isobutyl, t-butyl, amyl, hexyl, 2-ethylhexyl, etc.

10 The term "(lower)alkenyl" as used herein means both straight and branched chain alkenyl radicals containing from 2 to 8 carbon atoms, e.g. ethenyl, allyl, 1-propenyl, 1-but enyl, 3-but enyl, 2-methyl-1-propenyl, 3-pentenyl, 1-hexenyl, 7-octenyl, etc.

15 The term "(lower)alkynyl" as used herein means both straight and branched chain alkynyl radicals containing from 2 to 8 carbon atoms, e.g. ethynyl, propargyl, 1-butynyl, 2-butynyl, 1,1-dimethylpropargyl, 1-pentynyl, 1-heptynyl, etc.

20 Similarly, where the term "(lower)" is used as part of the description of another group, e.g., (lower)alkoxy, it refers to the alkyl portion of such group which is therefore as described in connection with (lower)alkyl.

Preferred compounds of the present invention are those having the following formulae

45 where *n*, *R*¹, *R*², *R*³, *R*⁴, *R*⁵ and *R*⁶ are as represented above.

Still more preferred compounds of the present invention are those having the following formulae

VII)

VIII)

herein n , R^1 , R^2 , R^3 and R^4 are as represented above.

The compounds of this invention are valuable pharmaceutical agents. They possess antifertility activity and are orally active antifertility agents in mammals.

The antifertility tests of the compounds of the present invention were carried out on mice. The compounds were administered orally to adult female mice for six days. A single dose was administered three days before mating and single doses were administered daily for five days during mating. The mice were sacrificed on the eleventh day following mating and their uteri examined for implantation sites. The absence of implantation sites in the uteri indicated that pregnancy was completely inhibited. When, for example, the preferred compound of the present invention, 3,4-dihydro-7-methoxy-3-phenyl-4-hydroxy-{p-[2-(1-pyrrolidyl)ethoxy]phenyl}-1H-2-benzothiophenone hydrochloride, was administered orally at doses as low as 0.1 mgm./kg./day, no implantation sites were observed in any of the mice tested; hence pregnancy was completely inhibited in each of the mice.

The compounds of the present invention are prepared by the following series of reactions.

A. A benzyl halide of the formula

X)

herein R^1 and R^2 are as described above, and Hal is chloro, bromo or iodo, is reacted with thiourea in the presence of an inert solvent, such as ethanol, at reflux temperature, and then the mixture is heated at reflux temperature in the presence of a base, such as sodium hydroxide, to produce a tolenethiol of the formula

)

herein R^1 and R^2 are as described above. This method is described by G. Urquhart, J. Gates and R. Connor, *J. Org. Chem.*, **18**, 363 (1953). An additional method of making the compounds of Formula X is described in Richter's *Organic Chemistry*, vol. III, 3rd Edition, at p. 5.

B. The tolenethiol prepared in Step A is reacted with α -halophenylacetic acid of the formula

I)

herein Hal, R^3 and R^4 are as described above, in the presence of a base such as sodium hydroxide and an inert

solvent such as ethanol at reflux temperature to produce a benzylthiophenylacetic acid of the formula

(XII)

5

10 wherein R^1 , R^2 , R^3 and R^4 are as described above.

C. The benzylthiophenylacetic acid prepared in Step B is cyclized by first reacting the compound with thionyl chloride in the presence of benzene at reflux temperature to convert the benzylthiophenylacetic acid to a benzylthiophenylacetyl chloride and then reacting the chloride with a dehydrating agent (Lewis acid), such as stannic chloride at a temperature of about 0°C. to produce a 3-phenyl-4-isothiocromanone of the formula

20 (XIII)

25

wherein R^1 , R^2 , R^3 and R^4 are as described above.

D. The compounds of the present invention are prepared by the reaction of the 3-phenyl-4-isothiocromanone prepared in Step C with a Grignard reagent of the formula

(XIV)

35

wherein Hal, n , X , R^5 and R^6 are as described above. The reaction is preferably carried out in the presence of an inert solvent, e.g. tetrahydrofuran, and at the boiling point

40 of the reaction mixture.

Alternatively, the compounds of the present invention may be prepared by the reaction of the 3-phenyl-4-isothiocromanone with an organo-lithium compound of the formula

45 (XV)

wherein n , X , R^5 and R^6 are as represented above.

50 The starting materials used in the processes described herein are compounds which are either commercially available, well-known in the art, or easily prepared in accordance with standard organic procedures previously described in the chemical literature.

55 For example, the benzyl halides used in Step A are prepared by the halogenation of a benzyl alcohol of the formula

(XVI)

60

wherein R^1 and R^2 are as described above, with a hydrogen halide gas, e.g., hydrogen chloride, in the presence of an inert solvent such as ethyl ether. An alternate method of preparing the benzyl halides consists of reacting a benzyl alcohol with thionyl chloride in the presence of pyridine. Methods for the preparation of benzyl halides are described by L. A. Brooks and H. R. Snyder, *Org. Syn.*, **30**, 698; Tsukamoto et al., *Pharm. Bull. (Japan)*, **3**, 239 (1955); *Textbook of Organic Chemistry*, Fieser and Fieser, 1950, pp. 430, 517-518; and Richter's *Organic Chemistry*, A. J. Mee, 3rd Edition, **75**, vol. III, p. 253.

The Grignard reagents having the Formula XIV used in Step D are prepared by procedures well-known in the art. The reagents are prepared by the reaction of magnesium with a halo-benzene of the formula

(XVII)

wherein Hal, X, n, R⁵ and R⁶ are as described above, in the presence of an inert solvent, e.g., tetrahydrofuran. The halobenzenes of Formula XVII used in the preparation of the Grignard reagents are prepared by well-known procedures, e.g. cf. A. Burger, E. L. Wilson, C. O. Brindley and F. Bernheim, J. Am. Chem. Soc., vol. 67, pp. 1416-1419 (1945); and South African Patent No. 62/3,277, which describe the reaction of a halo-phenol or a halo-thiophenol with a tertiary aminoalkyl halide of the formula

(XVIII)

wherein Hal, n, R⁵ and R⁶ are as described above, in an inert solvent, e.g. methanol, ethanol, and in the presence of a base such as sodium hydroxide. The tertiary aminoalkyl halides of Formula XVIII are prepared by the halogenation of a tertiary aminoalkanol as described by Burger et al. Such tertiary aminoalkanols may be prepared by the condensation reaction of a secondary amine of the formula

(XIX)

wherein R⁵ and R⁶ are as described above, and a halo alkanol of the formula

(X)

wherein Hal and n are as described above, as described by R. B. Moffett, J. Org. Chem., vol. 14, p. 862 (1949). The tertiary aminoalkanols can also be prepared by heating a secondary amine of Formula XIX with a halo alkanoic acid ester and then reducing the aminoalkanoic acid ester thus formed with a reducing agent such as lithium aluminum hydride, as described by Moffett. The preparation of each of the foregoing intermediates used in the preparation of the Grignard reagents is well-known in the art.

The compounds of this invention may be administered as the free bases or in the form of their nontoxic addition salts. They may be compounded and formulated into pharmaceutical preparations in unit dosage form for oral administration with organic or inorganic solid materials or liquids which are pharmaceutically acceptable carriers. The compositions may take the form of tablets, powder granules, capsules, suspensions, solutions and the like. Such compositions are considered within the scope of this invention.

The compositions of this invention when administered orally, in an effective amount, are effective in the inhibition of pregnancy. The usual daily dosage is from about 0.1 to 200 mgm./kg.

The following examples are intended to illustrate the invention described herein without unduly restricting it.

EXAMPLE 1

Preparation of *m*-methoxy- α -toluenethiolA solution of *m*-methoxybenzyl chloride (79.5 gm.), thiourea (38.6 gm.), and ethanol (250 ml.) was refluxed

on a steam cone for four hours. Sodium hydroxide (30.4 gm.) in water (300 ml.) was then added and the mixture refluxed under a nitrogen atmosphere for 2.5 hours.

The mixture was cooled and the lower layer of crude mercaptan separated. The aqueous phase was acidified with dilute sulfuric acid and then extracted with ether. The ether extracts were added to the crude mercaptan layer and the whole was washed with water and then dried over anhydrous magnesium sulfate. The solvent was removed and the residual oil (67 gm.) distilled at 118-130° C./0.65-0.70 mm. to yield 59.2 gm. (76%) of *m*-methoxy- α -toluenethiol as a colorless liquid. The major portion distilled at 119° C./0.65 mm.; n_D^{22} =1.5720; iodine equivalent, 152 (calcd. for $C_8H_{10}OS$, 154).

EXAMPLE 2

Preparation of (*m*-methoxybenzylthio)phenylacetic acidA solution of *m*-methoxy- α -toluenethiol (39.2 gm.) and α -bromophenylacetic acid (54.8 gm.) in ethanol (185 ml.) and aqueous sodium hydroxide (1 N, 508 ml.) was stirred at 22° C. for 17 hours.

About one-third of the solvent was removed at 15 mm., and the residue was extracted with two portions of ether which were discarded. The aqueous phase was then acidified with dilute hydrochloric acid and extracted several times with ether. The combined ether extracts were washed with water, dried and evaporated to give the product, (*m*-methoxybenzylthio)phenylacetic acid, as a deep yellow syrup; yield 68.8 gm. (94%).

The material was characterized as the hydrated sodium salt, M.P. 93-95° C. (dioxane-ether).

Analysis.—Calcd. for $C_{16}H_{15}NaO_3S \cdot H_2O$: C, 58.58; H, 5.22. Found: C, 58.70; H, 4.76.

EXAMPLE 3

Preparation of 7-methoxy-3-phenyl-4-*isothiocromanone*A mixture of the crude (*m*-methoxybenzylthio)phenylacetic acid (31.7 gm.), thionyl chloride (39.2 gm.) and benzene (75 ml.) was stirred at reflux for 25 minutes. The solution was concentrated at reduced pressure (2 mm.), fresh benzene added and the solution again concentrated; the operation was repeated to ensure complete removal of the thionyl chloride.

The crude acid chloride thus obtained was dissolved in benzene (100 ml.) and the solution stirred at 0-5° C. while a solution of stannic chloride (18.8 ml.) in benzene (48 ml.) was added over a 15-minute period. The mixture was stirred at 0° C. for an additional 1 minute, then poured onto a mixture of concentrated hydrochloric acid (165 ml.) and ice.

Trituration gave brown solid which was extracted in ether. The ether was washed in succession with water, aqueous sodium bicarbonate, water and saturated brine solution. After drying, the ether solution was stirred with decolorizing carbon for 1.5 hours. Filtration and evaporation of the ether gave a syrup which was triturated with "Skellysolve B" to give brown crystalline solid, yield 22.5 gm. (76%), M.P. 70-73° C.

Further recrystallizations from acetone-*Skellysolve B* gave the ketone of constant M.P. 85-86° C.

Analysis.—Calcd. for $C_{16}H_{14}O_2S$: C, 71.08; H, 5.22; S, 11.86; MW, 270. Found: C, 71.05; H, 5.21; S, 11.76; IW, 291 (ethanol, Mechrolab osmometer).

EXAMPLE 4

*Preparation of 1-[2-(p-bromophenoxy)ethyl]pyrrolidine*N-(2-chloroethyl)pyrrolidine hydrochloride (31.6 gm.) was added to a solution of sodium methoxide (9.2 gm.) in absolute ethanol (75 ml.). After stirring for 15 minutes at 25° C., sodium chloride was separated by filtration. The filtrate was added slowly over a period of 30 minutes to a hot solution of p-bromophenol (40.9 gm.) in absolute ethanol (225 ml.) containing sodium methoxide (12.7 gm.).

After heating under reflux for three hours, the mixture was cooled, the precipitated salt was separated, and the solvent was removed under reduced pressure. The residual oil was dissolved in ether which was washed in succession with 10% aqueous sodium hydroxide solution, water and saturated brine solution. Removal of the ether and distillation of the residue gave 26.0 gm. of 1-[2-(p-bromophenoxy)ethyl]pyrrolidine, B.P. 138–140° C./1.2 mm.

Analysis.—Calcd. for $C_{12}H_{16}BrNO$: NE, 270. Found: 1.

EXAMPLE 5

*Preparation of 1-[2-(p-bromophenylthio)ethyl]pyrrolidine*N-(2-chloroethyl)pyrrolidine hydrochloride (23.8 gm.) was added to a solution of sodium methoxide (6.9 gm.) in absolute ethanol (55 ml.). After stirring for 15 minutes at 25° C., the sodium chloride was separated, and the resultant clear solution was added dropwise over a period of one hour to a solution under reflux of p-bromophenol (33.6 gm.) in absolute ethanol (170 ml.) containing sodium methoxide (9.6 gm.).

After heating under reflux for three hours, the mixture was cooled, the precipitated salt was separated and the solvent was removed under reduced pressure. The residual oil was dissolved in ether, and the solution was treated in succession with 10% aqueous sodium hydroxide solution, water and saturated brine solution. After removal of the solvent, distillation gave 22.3 gm. of 1-[2-(p-bromophenylthio)ethyl]pyrrolidine, B.P. 8° C./1.1 mm.

Analysis.—Calcd. for $C_{12}H_{16}BrNS$: C, 50.35; H, 5.64; S, 27.92; N, 4.89. Found: C, 50.80; H, 5.62; Br, 28.40; 4.90.

EXAMPLE 6

*Preparation of 3,4-dihydro-7-methoxy-3-phenyl-4-hydroxy-4-[p-[2-(1-pyrrolidyl)ethoxy]phenyl]-1H-2-benzothiopyran hydrochloride*About one-tenth of a solution of 1-[2-(p-bromophenoxy)ethyl]pyrrolidine (6.70 gm.) in 70 ml. of dry tetrahydrofuran was added to magnesium turnings (0.60 gm.) contained in a nitrogen atmosphere. A crystal of iodine was added and the mixture was heated at reflux. After filtration of the reaction, the remaining pyrrolidine solution was added and the mixture stirred at reflux until essentially all of the magnesium had dissolved (two hrs.).

A solution of 7-methoxy-3-phenyl-4-isothiochromanone (6.70 gm.) in 74 ml. of dry tetrahydrofuran then was added rapidly and the resultant solution heated at reflux for 16 hours.

5 The mixture was cooled, ether added, and then water (2.5 ml.) introduced dropwise while cooling in an ice bath. The precipitated magnesium salts were separated by filtration. The filtrate was diluted with additional ether and then washed several times with water, dried and evaporated.

10 The residual oil was taken up in ether which then was extracted with three 25-ml. portions of 0.5 N hydrochloric acid. The combined acid extracts were extracted with methylene chloride. Drying (sodium sulfate) and evaporation of the methylene chloride gave the alcohol as an oil; yield 4.5 gm. Trituration under acetone yielded 1.50 gm. crystalline solid, M.P. 158–162° C. Recrystallization from methylene chloride-ethyl acetate gave 0.9 gm., M.P. 176–177° C. with decomposition.

20 *Analysis.*—Calcd. for $C_{28}H_{32}ClNO_3S$: C, 67.52; H, 6.50; N, 2.81. Found: C, 66.95; H, 6.49; N, 2.76, 2.91.

EXAMPLE 7

When, in the procedure of Example 1, m-methoxybenzyl chloride is replaced by an equal molar amount of benzyl chloride,

- 2-methoxybenzyl chloride,
4-methoxybenzyl chloride,
2,4-dimethoxybenzyl chloride,
3,5-dimethoxybenzyl chloride,
2,3-dimethoxybenzyl chloride,
3,4-dimethoxybenzyl chloride,
3-ethoxybenzyl chloride,
3-propoxybenzyl chloride,
3-chlorobenzyl chloride,
3-methylbenzyl chloride,
4-ethylbenzyl chloride,
2,4-dimethylbenzyl chloride,
2-propylbenzyl chloride,
3-trifluoromethylbenzyl chloride,
4-iodobenzyl chloride,
2-bromobenzyl chloride,
3-fluorobenzyl chloride,
3,4-dichlorobenzyl chloride,
3-phenylbenzyl chloride,
4-benzylbenzyl chloride,
2-phenoxybenzyl chloride,
3-dimethylaminobenzyl chloride,
4-dimethylsulfamylbenzyl chloride,
50 3-acetylbenzyl chloride,
3-methoxy-4-methylbenzyl chloride,
3-cyclohexylbenzyl chloride,
2-cyclopentylbenzyl chloride,
4-cycloheptylbenzyl chloride and
55 3-methoxy-4-trifluoromethylbenzyl chloride,
respectively, there are obtained,
α-toluenethiol,
2-methoxy-α-toluenethiol,
4-methoxy-α-toluenethiol,
2,4-dimethoxy-α-toluenethiol,
3,5-dimethoxy-α-toluenethiol,
2,3-dimethoxy-α-toluenethiol,
3,4-dimethoxy-α-toluenethiol,
60 3-ethoxy-α-toluenethiol,
3-propoxy-α-toluenethiol,
3-chloro-α-toluenethiol,
3-methyl-α-toluenethiol,
4-ethyl-α-toluenethiol,
2,4-dimethyl-α-toluenethiol,
70 2-propyl-α-toluenethiol,
3-trifluoromethyl-α-toluenethiol,
4-iodo-α-toluenethiol,
2-bromo-α-toluenethiol,
75 3-fluoro-α-toluenethiol,

3,4-dichloro- α -toluenethiol,
 3-phenyl- α -toluenethiol,
 4-benzyl- α -toluenethiol,
 2-phenoxy- α -toluenethiol,
 3-dimethylamino- α -toluenethiol,
 4-dimethylsulfamyl- α -toluenethiol,
 3-acetyl- α -toluenethiol,
 3-methoxy-4-methyl- α -toluenethiol,
 3-cyclohexyl- α -toluenethiol,
 2-cyclopentyl- α -toluenethiol,
 4-cycloheptyl- α -toluenethiol and
 3-methoxy-4-trifluoromethyl- α -toluenethiol,
 respectively.

EXAMPLE 8

When, in the procedure of Example 2, m-methoxy- α -toluenethiol is replaced by an equal molar amount of each of the products of Example 7, there are obtained, benzylthiophenylacetic acid,
 (2-methoxybenzylthio) phenylacetic acid,
 (4-methoxybenzylthio) phenylacetic acid,
 (2,4-dimethoxybenzylthio) phenylacetic acid,
 (3,5-dimethoxybenzylthio) phenylacetic acid,
 (2,3-dimethoxybenzylthio) phenylacetic acid,
 (3,4-dimethoxybenzylthio) phenylacetic acid,
 (3-ethoxybenzylthio) phenylacetic acid,
 (3-propoxybenzylthio) phenylacetic acid,
 (3-chlorobenzylthio) phenylacetic acid,
 (3-methylbenzylthio) phenylacetic acid,
 (4-ethylbenzylthio) phenylacetic acid,
 (2,4-dimethylbenzylthio) phenylacetic acid,
 (2-propylbenzylthio) phenylacetic acid,
 (3-trifluoromethylbenzylthio) phenylacetic acid,
 (4-iodobenzylthio) phenylacetic acid,
 (2-bromobenzylthio) phenylacetic acid,
 (3-fluorobenzylthio) phenylacetic acid,
 (3,4-dichlorobenzylthio) phenylacetic acid,
 (3-phenylbenzylthio) phenylacetic acid,
 (4-benzylbenzylthio) phenylacetic acid,
 (2-phenoxybenzylthio) phenylacetic acid,
 (3-dimethylaminobenzylthio) phenylacetic acid,
 (4-dimethylsulfamylbenzylthio) phenylacetic acid,
 (3-acetylbenzylthio) phenylacetic acid,
 (3-methoxy-4-methylbenzylthio) phenylacetic acid,
 (3-cyclohexylbenzylthio) phenylacetic acid,
 (2-cyclopentylbenzylthio) phenylacetic acid,
 (4-cycloheptylbenzylthio) phenylacetic acid and
 (3-methoxy-4-trifluoromethylbenzylthio) phenylacetic acid,
 respectively.

EXAMPLE 9

When, in the procedure of Example 2, α -bromophenylacetic acid is replaced by an equal molar amount of α -bromo-4-methylphenylacetic acid,
 α -bromo-4-trifluoromethylphenylacetic acid,
 α -bromo-2-chlorophenylacetic acid,
 α -bromo-3-bromophenylacetic acid,
 α -bromo-4-iodophenylacetic acid,
 α -bromo-3-fluorophenylacetic acid,
 α -bromo-2-ethylphenylacetic acid,
 α -bromo-2,4-dichlorophenylacetic acid,
 α -bromo-4-methoxyphenylacetic acid,
 α -bromo-3-ethoxyphenylacetic acid,
 α -bromo-2-propylphenylacetic acid,
 α -bromo-4-phenylphenylacetic acid,
 α -bromo-3-phenoxyphenylacetic acid,
 α -bromo-2-propoxyphenylacetic acid,
 α -bromo-2-methyl-4-trifluoromethylphenylacetic acid,
 α -bromo-4-benzylphenylacetic acid,
 α -bromo-3-cyclohexylphenylacetic acid,
 α -bromo-2-cyclopentylphenylacetic acid,
 α -bromo-4-acetylphenylacetic acid,
 α -bromo-3-dimethylsulfamylphenylacetic acid,

α -bromo-4-dimethylaminophenylacetic acid,
 α -bromo-3-diethylaminophenylacetic acid,
 α -bromo-4-fluorophenylacetic acid,
 α -bromo-4-chlorophenylacetic acid,
 α -bromo-2-diethylaminophenylacetic acid,
 α -bromo-3-cycloheptylphenylacetic acid,
 α -bromo-4-bromophenylacetic acid and
 α -bromo-3-propanoylphenylacetic acid,
 respectively there are obtained,
 m-methoxybenzylthio-4-methylphenylacetic acid,
 m-methoxybenzylthio-4-trifluoromethylphenylacetic acid,
 m-methoxybenzylthio-2-chlorophenylacetic acid,
 m-methoxybenzylthio-3-bromophenylacetic acid,
 α -bromo-4-iodophenylacetic acid,
 α -bromo-3-fluorophenylacetic acid,
 α -bromo-2-ethylphenylacetic acid,
 α -bromo-2,4-dichlorophenylacetic acid,
 α -bromo-4-methoxyphenylacetic acid,
 α -bromo-3-ethoxyphenylacetic acid,
 α -bromo-2-propylphenylacetic acid,
 α -bromo-4-phenylphenylacetic acid,
 α -bromo-3-phenoxyphenylacetic acid,
 α -bromo-2-propoxyphenylacetic acid,
 α -bromo-2-methyl-4-trifluoromethylphenylacetic acid,
 α -bromo-4-benzylphenylacetic acid,
 α -bromo-3-cyclohexylphenylacetic acid,
 α -bromo-2-cyclopentylphenylacetic acid,
 α -bromo-4-acetylphenylacetic acid,
 α -bromo-3-dimethylsulfamylphenylacetic acid,
 α -bromo-4-dimethylaminophenylacetic acid,
 α -bromo-3-diethylaminophenylacetic acid,
 α -bromo-4-fluorophenylacetic acid,
 α -bromo-4-chlorophenylacetic acid,
 α -bromo-2-diethylaminophenylacetic acid,
 α -bromo-3-cycloheptylphenylacetic acid,
 α -bromo-4-bromophenylacetic acid and
 α -bromo-3-propanoylphenylacetic acid,
 respectively.

EXAMPLE 10

When, in the procedure of Example 3, (m-methoxybenzylthio) phenylacetic acid is replaced by an equal molar amount of each of the products of Example 8, there are obtained,

3-phenyl-4-isothiocromanone,
 8-methoxy-3-phenyl-4-isothiocromanone,
 α -bromo-3-phenyl-4-isothiocromanone,
 6,8-dimethoxy-3-phenyl-4-isothiocromanone,
 5,7-dimethoxy-3-phenyl-4-isothiocromanone,
 7,8-dimethoxy-3-phenyl-4-isothiocromanone,
 6,7-dimethoxy-3-phenyl-4-isothiocromanone,
 α -bromo-3-phenyl-4-isothiocromanone,
 7-propoxy-3-phenyl-4-isothiocromanone,
 7-chloro-3-phenyl-4-isothiocromanone,
 7-methyl-3-phenyl-4-isothiocromanone,
 7-ethyl-3-phenyl-4-isothiocromanone,
 α -bromo-3-phenyl-4-isothiocromanone,
 6,8-dimethyl-3-phenyl-4-isothiocromanone,
 8-propyl-3-phenyl-4-isothiocromanone,
 7-trifluoromethyl-3-phenyl-4-isothiocromanone,
 6-iodo-3-phenyl-4-isothiocromanone,
 α -bromo-3-phenyl-4-isothiocromanone,
 α -bromo-3-phenyl-4-isothiocromanone,
 α -bromo-3-phenyl-4-isothiocromanone,
 7-fluoro-3-phenyl-4-isothiocromanone,
 6,7-dichloro-3-phenyl-4-isothiocromanone,
 7-phenyl-3-phenyl-4-isothiocromanone,
 6-benzyl-3-phenyl-4-isothiocromanone,
 8-phenoxy-3-phenyl-4-isothiocromanone,
 α -bromo-3-phenyl-4-isothiocromanone,
 7-dimethylamino-3-phenyl-4-isothiocromanone,
 6-dimethylsulfamyl-3-phenyl-4-isothiocromanone,
 7-acetyl-3-phenyl-4-isothiocromanone,
 6-methyl-7-methoxy-3-phenyl-4-isothiocromanone,
 7-cyclohexyl-3-phenyl-4-isothiocromanone,
 α -bromo-3-dimethylsulfamylphenylacetic acid,
 75 8-cyclopentyl-3-phenyl-4-isothiocromanone,

11

i-cycloheptyl-3-phenyl-4-isothiocromanone and *i*-trifluoromethyl-7-methoxy-3-phenyl-4-isothiocromanone, respectively.

EXAMPLE 11

When, in the procedure of Example 3, *m*-methoxy-*en*ylthiophenylacetic acid is replaced by an equal molar amount of each of the products of Example 9, there are obtained,

-methoxy-3-(4-methylphenyl)-4-isothiocromanone, -methoxy-3-(4-trifluoromethylphenyl)-4-isothiocromanone, -methoxy-3-(2-chlorophenyl)-4-isothiocromanone, -methoxy-3-(3-bromophenyl)-4-isothiocromanone, -methoxy-3-(4-iodophenyl)-4-isothiocromanone, -methoxy-3-(3-fluorophenyl)-4-isothiocromanone, -methoxy-3-(2-ethylphenyl)-4-isothiocromanone, -methoxy-3-(2,4-dichlorophenyl)-4-isothiocromanone, -methoxy-3-(4-methoxyphenyl)-4-isothiocromanone, -methoxy-3-(3-ethoxyphenyl)-4-isothiocromanone, -methoxy-3-(2-propylphenyl)-4-isothiocromanone, -methoxy-3-(4-phenylphenyl)-4-isothiocromanone, -methoxy-3-(3-phenoxyphenyl)-4-isothiocromanone, -methoxy-3-(2-propoxypyhenyl)-4-isothiocromanone, -methoxy-3-(2-methyl-4-trifluoromethylphenyl)-4-isothiocromanone, -methoxy-3-(4-benzylphenyl)-4-isothiocromanone, -methoxy-3-(3-cyclohexylphenyl)-4-isothiocromanone, -methoxy-3-(2-cyclopentylphenyl)-4-isothiocromanone, -methoxy-3-(4-acetylphenyl)-4-isothiocromanone, -methoxy-3-(3-dimethylsulfamylphenyl)-4-isothiocromanone, -methoxy-3-(4-dimethylaminophenyl)-4-isothiocromanone, -methoxy-3-(3-diethylaminophenyl)-4-isothiocromanone, -methoxy-3-(4-fluorophenyl)-4-isothiocromanone, -methoxy-3-(4-chlorophenyl)-4-isothiocromanone, -methoxy-3-(2-diethylaminophenyl)-4-isothiocromanone, -methoxy-3-(3-cycloheptylphenyl)-4-isothiocromanone, -methoxy-3-(4-bromophenyl)-4-isothiocromanone, and -methoxy-3-(3-propanoylphenyl)-4-isothiocromanone, respectively.

EXAMPLE 12

When, in the procedure of Example 6, 7-methoxy-3-phenyl-4-isothiocromanone is replaced by an equal molar amount of each of the products of Example 10, there are obtained,

4-dihydro-3-phenyl-4-hydroxy-4-{p-[2-(1-pyrrolidyl)ethoxy]phenyl}-1H-2-benzothiopyran, 4-dihydro-8-methoxy-3-phenyl-4-hydroxy-4-{p-[2-(1-pyrrolidyl)ethoxy]phenyl}-1H-2-benzothiopyran, 4-dihydro-6-methoxy-3-phenyl-4-hydroxy-4-{p-[2-(1-pyrrolidyl)ethoxy]phenyl}-1H-2-benzothiopyran, 4-dihydro-6,8-dimethoxy-3-phenyl-4-hydroxy-4-{p-[2-(1-pyrrolidyl)ethoxy]phenyl}-1H-2-benzothiopyran, 4-dihydro-5,7-dimethoxy-3-phenyl-4-hydroxy-4-{p-[2-(1-pyrrolidyl)ethoxy]phenyl}-1H-2-benzothiopyran, 4-dihydro-7,8-dimethoxy-3-phenyl-4-hydroxy-4-{p-[2-(1-pyrrolidyl)ethoxy]phenyl}-1H-2-benzothiopyran, 4-dihydro-6,7-dimethoxy-3-phenyl-4-hydroxy-4-{p-[2-(1-pyrrolidyl)ethoxy]phenyl}-1H-2-benzothiopyran, 4-dihydro-7-ethoxy-3-phenyl-4-hydroxy-4-{p-[2-(1-pyrrolidyl)ethoxy]phenyl}-1H-2-benzothiopyran, 4-dihydro-7-propoxy-3-phenyl-4-hydroxy-4-{p-[2-(1-pyrrolidyl)ethoxy]phenyl}-1H-2-benzothiopyran, 4-dihydro-7-chloro-3-phenyl-4-hydroxy-4-{p-[2-(1-pyrrolidyl)ethoxy]phenyl}-1H-2-benzothiopyran, 4-dihydro-7-methyl-3-phenyl-4-hydroxy-4-{p-[2-(1-pyrrolidyl)ethoxy]phenyl}-1H-2-benzothiopyran,

12

3,4-dihydro-6-ethyl-3-phenyl-4-hydroxy-4-{p-[2-(1-pyrrolidyl)ethoxy]phenyl}-1H-2-benzothiopyran, 3,4-dihydro-6,8-dimethyl-3-phenyl-4-hydroxy-4-{p-[2-(1-pyrrolidyl)ethoxy]phenyl}-1H-2-benzothiopyran, 5 3,4-dihydro-8-propyl-3-phenyl-4-hydroxy-4-{p-[2-(1-pyrrolidyl)ethoxy]phenyl}-1H-2-benzothiopyran, 3,4-dihydro-7-trifluoromethyl-3-phenyl-4-hydroxy-4-{p-[2-(1-pyrrolidyl)ethoxy]phenyl}-1H-2-benzothiopyran, 3,4-dihydro-6-iodo-3-phenyl-4-hydroxy-4-{p-[2-(1-pyrrolidyl)ethoxy]phenyl}-1H-2-benzothiopyran, 10 3,4-dihydro-8-bromo-3-phenyl-4-hydroxy-4-{p-[2-(1-pyrrolidyl)ethoxy]phenyl}-1H-2-benzothiopyran, 3,4-dihydro-7-fluoro-3-phenyl-4-hydroxy-4-{p-[2-(1-pyrrolidyl)ethoxy]phenyl}-1H-2-benzothiopyran, 15 3,3,4-dihydro-6,7-dichloro-3-phenyl-4-hydroxy-4-{p-[2-(1-pyrrolidyl)ethoxy]phenyl}-1H-2-benzothiopyran, 3,4-dihydro-7-phenyl-3-phenyl-4-hydroxy-4-{p-[2-(1-pyrrolidyl)ethoxy]phenyl}-1H-2-benzothiopyran, 3,4-dihydro-6-benzyl-3-phenyl-4-hydroxy-4-{p-[2-(1-pyrrolidyl)ethoxy]phenyl}-1H-2-benzothiopyran, 20 3,4-dihydro-8-phenoxy-3-phenyl-4-hydroxy-4-{p-[2-(1-pyrrolidyl)ethoxy]phenyl}-1H-2-benzothiopyran, 3,4-dihydro-7-dimethylamino-3-phenyl-4-hydroxy-4-{p-[2-(1-pyrrolidyl)ethoxy]phenyl}-1H-2-benzothiopyran, 25 3,4-dihydro-6-dimethylsulfamyl-3-phenyl-4-hydroxy-4-{p-[2-(1-pyrrolidyl)ethoxy]phenyl}-1H-2-benzothiopyran, 3,4-dihydro-7-acetyl-3-phenyl-4-hydroxy-4-{p-[2-(1-pyrrolidyl)ethoxy]phenyl}-1H-2-benzothiopyran, 3,4-dihydro-6-methyl-7-methoxy-3-phenyl-4-hydroxy-4-{p-[2-(1-pyrrolidyl)ethoxy]phenyl}-1H-2-benzothiopyran, 30 3,4-dihydro-7-cyclohexyl-3-phenyl-4-hydroxy-4-{p-[2-(1-pyrrolidyl)ethoxy]phenyl}-1H-2-benzothiopyran, 3,4-dihydro-8-cyclopentyl-3-phenyl-4-hydroxy-4-{p-[2-(1-pyrrolidyl)ethoxy]phenyl}-1H-2-benzothiopyran, 35 3,4-dihydro-6-cycloheptyl-3-phenyl-4-hydroxy-4-{p-[2-(1-pyrrolidyl)ethoxy]phenyl}-1H-2-benzothiopyran, and 3,4-dihydro-6-trifluoromethyl-7-methoxy-3-phenyl-4-hydroxy-4-{p-[2-(1-pyrrolidyl)ethoxy]phenyl}-1H-2-benzothiopyran,

40 respectively.

EXAMPLE 13

When, in the procedure of Example 6, 7-methoxy-3-phenyl-4-isothiocromanone is replaced by an equal molar amount of each of the products of Example 11, there are obtained,

3,4-dihydro-7-methoxy-3-(4-methylphenyl)-4-hydroxy-4-{p-[2-(1-pyrrolidyl)ethoxy]phenyl}-1H-2-benzothiopyran, 50 3,4-dihydro-7-methoxy-3-(4-trifluoromethylphenyl)-4-hydroxy-4-{p-[2-(1-pyrrolidyl)ethoxy]phenyl}-1H-2-benzothiopyran, 3,4-dihydro-7-methoxy-3-(2-chlorophenyl)-4-hydroxy-4-{p-[2-(1-pyrrolidyl)ethoxy]phenyl}-1H-2-benzothiopyran, 55 3,4-dihydro-7-methoxy-3-(3-bromophenyl)-4-hydroxy-4-{p-[2-(1-pyrrolidyl)ethoxy]phenyl}-1H-2-benzothiopyran, 3,4-dihydro-7-methoxy-3-(3-diethylaminophenyl)-4-hydroxy-4-{p-[2-(1-pyrrolidyl)ethoxy]phenyl}-1H-2-benzothiopyran, 60 3,4-dihydro-7-methoxy-3-(4-iodophenyl)-4-hydroxy-4-{p-[2-(1-pyrrolidyl)ethoxy]phenyl}-1H-2-benzothiopyran, 3,4-dihydro-7-methoxy-3-(3-fluorophenyl)-4-hydroxy-4-{p-[2-(1-pyrrolidyl)ethoxy]phenyl}-1H-2-benzothiopyran, 65 3,4-dihydro-7-methoxy-3-(2-ethylphenyl)-4-hydroxy-4-{p-[2-(1-pyrrolidyl)ethoxy]phenyl}-1H-2-benzothiopyran, 3,4-dihydro-7-methoxy-3-(2,4-dichlorophenyl)-4-hydroxy-4-{p-[2-(1-pyrrolidyl)ethoxy]phenyl}-1H-2-benzothiopyran,

75 respectively,

3,4-dihydro-7-methoxy-3-(3-ethoxyphenyl)-4-hydroxy-4-{p-[2-(1-pyrrolidyl)ethoxy]phenyl}-1H-2-benzothiopyran,
 3,4-dihydro-7-methoxy-3-(2-propylphenyl)-4-hydroxy-4-{p-[2-(1-pyrrolidyl)ethoxy]phenyl}-1H-2-benzothiopyran,
 3,4-dihydro-7-methoxy-3-(4-phenylphenyl)-4-hydroxy-4-{p-[2-(1-pyrrolidyl)ethoxy]phenyl}-1H-2-benzothiopyran,
 3,4-dihydro-7-methoxy-3-(3-phenoxyphenyl)-4-hydroxy-4-{p-[2-(1-pyrrolidyl)ethoxy]phenyl}-1H-2-benzothiopyran,
 3,4-dihydro-7-methoxy-3-(2-propoxyphenyl)-4-hydroxy-4-{p-[2-(1-pyrrolidyl)ethoxy]phenyl}-1H-2-benzothiopyran,
 3,4-dihydro-7-methoxy-3-(2-methyl-4-trifluoromethylphenyl)-4-hydroxy-4-{p-[2-(1-pyrrolidyl)ethoxy]phenyl}-1H-2-benzothiopyran,
 3,4-dihydro-7-methoxy-3-(4-benzylphenyl)-4-hydroxy-4-{p-[2-(1-pyrrolidyl)ethoxy]phenyl}-1H-2-benzothiopyran,
 3,4-dihydro-7-methoxy-3-(3-cyclohexylphenyl)-4-hydroxy-4-{p-[2-(1-pyrrolidyl)ethoxy]phenyl}-1H-2-benzothiopyran,
 3,4-dihydro-7-methoxy-3-(2-cyclopentylphenyl)-4-hydroxy-4-{p-[2-(1-pyrrolidyl)ethoxy]phenyl}-1H-2-benzothiopyran,
 3,4-dihydro-7-methoxy-3-(4-acetylphenyl)-4-hydroxy-4-{p-[2-(1-pyrrolidyl)ethoxy]phenyl}-1H-2-benzothiopyran,
 3,4-dihydro-7-methoxy-3-(3-dimethylsulfamylphenyl)-4-hydroxy-4-{p-[2-(1-pyrrolidyl)ethoxy]phenyl}-1H-2-benzothiopyran,
 3,4-dihydro-7-methoxy-3-(4-dimethylaminophenyl)-4-hydroxy-4-{p-[2-(1-pyrrolidyl)ethoxy]phenyl}-1H-2-benzothiopyran,
 3,4-dihydro-7-methoxy-3-(3-diethylaminophenyl)-4-hydroxy-4-{p-[2-(1-pyrrolidyl)ethoxy]phenyl}-1H-2-benzothiopyran,
 3,4-dihydro-7-methoxy-3-(4-fluorophenyl)-4-hydroxy-4-{p-[2-(1-pyrrolidyl)ethoxy]phenyl}-1H-2-benzothiopyran,
 3,4-dihydro-7-methoxy-3-(4-chlorophenyl)-4-hydroxy-4-{p-[2-(1-pyrrolidyl)ethoxy]phenyl}-1H-2-benzothiopyran,
 3,4-dihydro-7-methoxy-3-(2-diethylaminophenyl)-4-hydroxy-4-{p-[2-(1-pyrrolidyl)ethoxy]phenyl}-1H-2-benzothiopyran,
 3,4-dihydro-7-methoxy-3-(3-cycloheptylphenyl)-4-hydroxy-4-{p-[2-(1-pyrrolidyl)ethoxy]phenyl}-1H-2-benzothiopyran,
 3,4-dihydro-7-methoxy-3-(4-bromophenyl)-4-hydroxy-4-{p-[2-(1-pyrrolidyl)ethoxy]phenyl}-1H-2-benzothiopyran,
 3,4-dihydro-7-methoxy-3-(3-propanoylphenyl)-4-hydroxy-4-{p-[2-(1-pyrrolidyl)ethoxy]phenyl}-1H-2-benzothiopyran,
 respectively.

EXAMPLE 14

When, in the procedure of Example 6, 1-[2-(p-bromophenoxy)ethyl]pyrrolidine is replaced by an equal molar amount of

1-[2-(p-bromophenylthio)ethyl]pyrrolidine,
 1-[2-(p-bromophenoxy)ethyl]piperidine,
 1-[2-(p-bromophenylthio)ethyl]piperidine,
 1-[2-(p-bromophenylthio)ethyl]pyrrolidine,
 1-[p-bromophenoxy-methyl]pyrrolidine,
 1-[2-(p-bromophenoxy)ethyl]-2-methylpyrrolidine,
 1-[2-(p-bromophenoxy)ethyl]-2,4-dimethylpyrrolidine,
 1-[2-(p-bromophenoxy)ethyl]-3-ethylpyrrolidine,
 1-[2-(p-bromophenoxy)ethyl]-3-butylpyrrolidine,
 1-[2-(p-bromophenoxy)ethyl]-2,4-dimethylpiperidine,
 1-[2-(p-bromophenoxy)ethyl]-3-methylpiperidine,
 1-[2-(p-bromophenoxy)ethyl]-4-propylpiperidine,

1-[2-(p-bromophenoxy)ethyl]-4-methylpiperidine,
 4-[2-(p-bromophenoxy)ethyl]morpholine,
 4-[2-(p-bromophenoxy)ethyl]-2-methylmorpholine,
 4-[2-(p-bromophenoxy)ethyl]-3-ethylmorpholine,
 5 4-[2-(p-bromophenoxy)ethyl]-2,6-dimethylmorpholine,
 1-[2-(p-bromophenoxy)ethyl]-4-methyl-1,2,5,6-tetrahydropyridine,
 1-[2-(p-bromophenoxy)ethyl]-4-methylpiperazine,
 1-[2-(p-bromophenoxy)ethyl]-2,4-dimethylpiperazine,
 10 1-[2-(p-bromophenoxy)ethyl]-2,4,6-trimethylpiperazine,
 1-[2-(p-bromophenoxy)ethyl]hexamethyleneimine,
 1-[2-(p-bromophenoxy)ethyl]-2-methylhexamethyleneimine,
 15 1-[2-(p-bromophenoxy)ethyl]-2,4-dimethylhexamethyleneimine,
 1-[2-(p-bromophenoxy)isopropyl]pyrrolidine,
 1-[3-(p-bromophenoxy)propyl]pyrrolidine,
 1-[4-(p-bromophenoxy)butyl]pyrrolidine,
 20 4-[2-(p-bromophenylthio)ethyl]morpholine,
 1-[2-(p-bromophenylthio)ethyl]-4-methylpiperazine,
 1-[2-(p-bromophenylthio)ethyl]hexamethyleneimine,
 p-(2-N,N-dibutylaminoethoxy)bromobenzene,
 p-(2-N,N-dimethylaminoethoxy)bromobenzene,
 25 p-(2-N,N-diallylaminoethoxy)bromobenzene,
 p-(2-N,N-dipropargylaminoethoxy)bromobenzene,
 p-(2-N,N-dicyclopropylaminoethoxy)bromobenzene,
 p-(2-N,N-dibutylaminoethoxy)bromobenzene,
 p-(2-N,N-diethylaminoethoxy)bromobenzene,
 30 p-(2-N,N-dipropylaminoethoxy)bromobenzene,
 p-(2-N,N-diethenylaminoethoxy)bromobenzene,
 p-(2-N,N-dipropenylaminoethoxy)bromobenzene,
 p-(2-N,N-dihexenylaminoethoxy)bromobenzene,
 35 p-(2-N,N-dicinnamylaminoethoxy)bromobenzene,
 p-(2-N,N-dibenzylaminoethoxy)bromobenzene,
 p-(2-N,N-diphenethylaminoethoxy)bromobenzene,
 p-(2-N,N-dihexylaminoethoxy)bromobenzene,
 p-(2-N-cyclopropyl-N-phenylaminoethoxy)bromobenzene,
 40 p-(2-N-benzyl-N-cyclopropylaminoethoxy)bromobenzene,
 p-(2-N,N-diphenylaminoethoxy)bromobenzene,
 p-(2-N-methyl-N-phenylaminoethoxy)bromobenzene,
 p-(2-N,N-dicyclohexylaminoethoxy)bromobenzene,
 45 p-(2-N,N-dicyclobutylaminoethoxy)bromobenzene,
 p-(2-N,N-dicycloheptylaminoethoxy)bromobenzene,
 p-(2-N,N-dimethylaminoethylthio)bromobenzene,
 p-(2-N,N-diallylaminethylthio)bromobenzene,
 p-(2-N,N-dipropargylaminethylthio)bromobenzene,
 50 p-(2-N,N-dicyclopropylaminethylthio)bromobenzene,
 p-(2-N,N-diethylaminoethylthio)bromobenzene,
 p-(2-N,N-dibutylaminoethylthio)bromobenzene,
 p-(2-N,N-dicyclohexylaminoethylthio)bromobenzene,
 55 p-(2-N,N-dibenzylaminoethylthio)bromobenzene,
 p-(3-N,N-diethylaminopropylthio)bromobenzene,
 p-(4-N,N-diethylaminobutylthio)bromobenzene,
 p-(2-N,N-diethylaminoethylthio)bromobenzene,
 o-(2-N,N-diethylaminoethoxy)bromobenzene,
 60 m-(2-N,N-diethylaminoethoxy)bromobenzene,
 o-(2-N,N-diethylaminoethylthio)bromobenzene,
 m-(2-N,N-diethylaminoethylthio)bromobenzene,
 1-[2-(o-bromophenoxy)ethyl]pyrrolidine,
 1-[2-(m-bromophenoxy)ethyl]pyrrolidine,
 65 1-[2-(o-bromophenylthio)ethyl]pyrrolidine and 1-[2-(m-bromophenylthio)ethyl]pyrrolidine,

there are obtained,

70 3,4-dihydro-7-methoxy-3-phenyl-4-hydroxy-4-{p-[2-(1-pyrrolidyl)-ethylthio]phenyl}-1H-2-benzothiopyran,
 3,4-dihydro-7-methoxy-3-phenyl-4-hydroxy-4-{p-[2-(1-piperidino)-ethoxy]phenyl}-1H-2-benzothiopyran,
 3,4-dihydro-7-methoxy-3-phenyl-4-hydroxy-4-{p-[2-(1-piperidino)-ethylthio]phenyl}-1H-2-benzothiopyran,
 75

3,4-dihydro-7-methoxy-3-phenyl-4-hydroxy-4-{p-[2-(N,N-diphenylamino)ethylthio]phenyl}-1H-2-benzothiopyran,
 3,4-dihydro-7-methoxy-3-phenyl-4-hydroxy-4-{p-[2-(N,N-dibenzylamino)ethylthio]phenyl}-1H-2-benzothiopyran,
 3,4-dihydro-7-methoxy-3-phenyl-4-hydroxy-4-{p-[3-(N,N-diethylamino)propylthio]phenyl}-1H-2-benzothiopyran,
 3,4-dihydro-7-methoxy-3-phenyl-4-hydroxy-4-{p-[4-(N,N-diethylamino)butylthio]phenyl}-1H-2-benzothiopyran,
 3,4-dihydro-7-methoxy-3-phenyl-4-hydroxy-4-{p-[2-(N,N-diethylamino)ethylthio]phenyl}-1H-2-benzothiopyran,
 3,4-dihydro-7-methoxy-3-phenyl-4-hydroxy-4-{o-[2-(N,N-diethylamino)ethoxy]phenyl}-1H-2-benzothiopyran,
 3,4-dihydro-7-methoxy-3-phenyl-4-hydroxy-4-{m-[2-(N,N-diethylamino)ethoxy]phenyl}-1H-2-benzothiopyran,
 3,4-dihydro-7-methoxy-3-phenyl-4-hydroxy-4-{o-[2-(1-pyrrolidyl)ethoxy]phenyl}-1H-2-benzothiopyran,
 3,4-dihydro-7-methoxy-3-phenyl-4-hydroxy-4-{m-[2-(1-pyrrolidyl)ethoxy]phenyl}-1H-2-benzothiopyran,
 3,4-dihydro-7-methoxy-3-phenyl-4-hydroxy-4-{o-[2-(1-pyrrolidyl)ethylthio]phenyl}-1H-2-benzothiopyran and
 3,4-dihydro-7-methoxy-3-phenyl-4-hydroxy-4-{m-[2-(1-pyrrolidyl)ethylthio]phenyl}-1H-2-benzothiopyran,
 respectively.

EXAMPLE 15

Preparation of 3,4-dihydro-7-methoxy-3-phenyl-4-hydroxy-4-{p-[2-(diethylamino)ethoxy]phenyl}-1H-2-benzothiopyran hydrochloride

Using the procedure described above in Example 6, a Grignard reagent was prepared from p-(2-diethylaminoethoxy)bromobenzene (10.10 gm.) and magnesium turnings (0.90 gm.) in tetrahydrofuran (105 ml.).

A solution of 7-methoxy-3-phenyl-4-isothiocromanone (10.00 gm.) in tetrahydrofuran (110 ml.) then was added rapidly to the hot Grignard solution and the resultant solution was heated at reflux for 16 hours.

The mixture was cooled, ether was added, and then water (3.7 ml.) was introduced slowly while cooling in an ice bath. The precipitated magnesium salts were separated by filtration. The filtrate was diluted with additional ether and the resultant solution was washed several times with water, dried and concentrated.

The residual oil was taken up in ether and the solution was extracted with three 39-ml. portions of 0.5 N hydrochloric acid. The combined acid extracts were extracted with methylene chloride. Drying (sodium sulfate) and evaporation of the methylene chloride gave 3,4-dihydro-7-methoxy-3-phenyl-4-hydroxy-4-{p-[2-(diethylamino)ethoxy]phenyl}-1H-2-benzothiopyran as an oil. Trituration under a mixture of methylene chloride and ethyl acetate gave 1.95 gm. (11%) crystalline solid, 3,4-dihydro-7-methoxy-3-phenyl-4-hydroxy-4-{p-[2-(diethylamino)ethoxy]phenyl}-1H-2-benzothiopyran hydrochloride, M.P. 169-170° C. with decomposition. The material was purified for analysis by recrystallization to a constant melting point of 186.5-187.5° C. with decomposition.

Analysis.—Calcd. for C₂₈H₃₄ClNO₃S: C, 67.25; H, 6.85; Cl, 7.09; N, 2.79; S, 6.41. Found: C, 67.30, 67.22; H, 6.96, 6.96; Cl, 6.86; N, 2.73; S, 6.45.

Thus, it is apparent from the foregoing description that

the objects of this invention have been attained. Novel compounds have been invented which have antifertility activity and inhibit pregnancy. In addition, a novel method of inhibiting pregnancy has been described.

While this invention has been described and exemplified in terms of its preferred embodiment, those skilled in the art will appreciate that modifications can be made without departing from the spirit and scope of this invention.

What is claimed is:

1. A compound selected from the group consisting of compounds of the formula

wherein

n is a whole integer from 1 to 6 inclusive;

R¹, R², R³ and R⁴ each represent a member selected from the group consisting of hydrogen, chloro, bromo, iodo, fluoro, trifluoromethyl, (lower)alkyl, (lower)alkoxy, di(lower)alkylamino, di(lower)alkylsulfamyl, (lower)alkanoyl, phenyl, phenoxy, benzyl and cycloalkyl radicals having from 5 to 7 carbon atoms inclusive;

R⁵ and R⁶ each represent a member selected from the group consisting of (lower)alkyl, (lower)alkenyl, (lower)alkynyl, phenyl, phenyl(lower)alkyl, cycloalkyl radicals having from 3 to 7 carbon atoms inclusive, and when taken together with $-N<$, constitute a heterocyclic ring selected from the group consisting of pyrrolidino, (lower)alkylpyrrolidino, di(lower)alkylpyrrolidino, piperidino, (lower)alkylpiperidino, di(lower)alkylpiperidino, morpholino, (lower)alkylmorpholino, di(lower)alkylmorpholino, tetrahydropyridino, (lower)alkyltetrahydropyridino, di(lower)alkyltetrahydropyridino, N'-(lower)alkylpiperazino, N'-(lower)alkyl-(lower)alkylpiperazino, N'-(lower)alkyl-di(lower)alkylpiperazino, hexamethyleneimino, (lower)alkylhexamethyleneimino, di(lower)alkylhexamethyleneimino;

X is a member selected from the group consisting of oxygen and sulfur;

and the pharmaceutically acceptable nontoxic salts thereof.

2. A compound selected from the group consisting of compounds of the formula

wherein

n is a whole integer from 1 to 6 inclusive;

R¹, R², R³ and R⁴ each represent a member selected from the group consisting of hydrogen, chloro, bromo, iodo, fluoro, trifluoromethyl, (lower)alkyl, (lower)alkoxy, di(lower)alkylamino, di(lower)alkylsulfamyl, (lower)alkanoyl, phenyl, phenoxy, benzyl and cycloalkyl radicals having from 5 to 7 carbon atoms inclusive;

R^5 and R^6 each represent a member selected from the group consisting of (lower)alkyl, (lower)alkenyl, (lower)alkynyl, phenyl, phenyl(lower)alkyl, cycloalkyl radicals having from 3 to 7 carbon atoms inclusive, and when taken together with $-N<$, constitute a heterocyclic ring selected from the group consisting of pyrrolidino, (lower)alkylpyrrolidino, di(lower)alkylpyrrolidino, piperidino, (lower)alkylpiperidino, di(lower)alkylpiperidino, morpholino, (lower)alkylmorpholino, di(lower)alkylmorpholino, tetrahydropyridino, (lower)alkyltetrahydropyridino, di(lower)alkyltetrahydropyridino, N' -(lower)alkylpiperazino, N' -(lower)alkyl-(lower)alkylpiperazino, N' -(lower)alkyl-di(lower)alkylpiperazino, hexamethyleneimino, (lower)alkylhexamethyleneimino, di(lower)alkylhexamethyleneimino; and the pharmaceutically acceptable nontoxic salts thereof.

3. A compound selected from the group consisting of compounds of the formula

herein

n is a whole integer from 1 to 6 inclusive; R^1 , R^2 , R^3 and R^4 each represent a member selected from the group consisting of hydrogen, chloro, bromo, iodo, fluoro, trifluoromethyl, (lower)alkyl, (lower)alkoxy, di(lower)alkylamino, di(lower)alkylsulfamyl, (lower)alkanoyl, phenyl, phenoxy, benzyl and cycloalkyl radicals having from 5 to 7 carbon atoms inclusive;

R^5 and R^6 each represent a member selected from the group consisting of (lower)alkyl, (lower)alkenyl, (lower)alkynyl, phenyl, phenyl(lower)alkyl, cycloalkyl radicals having from 3 to 7 carbon atoms inclusive, and when taken together with $-N<$, constitute a heterocyclic ring selected from the group consisting of pyrrolidino, (lower)alkylpyrrolidino, di(lower)alkylpyrrolidino, piperidino, (lower)alkylpiperidino, di(lower)alkylpiperidino, morpholino, (lower)alkylmorpholino, di(lower)alkylmorpholino, tetrahydropyridino, (lower)alkyltetrahydropyridino, di(lower)alkyltetrahydropyridino, N' -(lower)alkylpiperazino, N' -(lower)alkyl-(lower)alkylpiperazino, N' -(lower)alkyl-di(lower)alkylpiperazino, hexamethyleneimino, (lower)alkylhexamethyleneimino, di(lower)alkylhexamethyleneimino; and the pharmaceutically acceptable nontoxic salts thereof.

4. A compound having the formula

herein

n is a whole integer from 1 to 6 inclusive.

5. A compound having the formula

wherein

n is a whole integer from 1 to 6 inclusive.

6. A compound having the formula

herein

n is a whole integer from 1 to 6 inclusive.

7. The compound having the formula

8. The pharmaceutically acceptable nontoxic salts of the compound of claim 7.

9. The compound having the formula

10. The compound having the formula

11. The compound having the formula

12. The compound having the formula

13. The compound having the formula
